UNITED STATES PATENT OFFICE.

RAPHAEL M. SELDIS, OF NEW YORK, N. Y.

DESIGN FOR A SKATING-MUFF.

Specification forming part of Design No. 5,943, dated June 18, 1872.

Specification describing a new and original Design for a Skating-Muff, invented by RAPHAEL MORRIS SELDIS, of New York, county and State of New York.

The drawing represents a perspective view of my new design for a muff.

Similar letters of reference indicate corresponding parts.

The invention relates to a design for a skating-muff; and consists in forming a pocket with the outside flap *a* in the shape of a quad-

rilateral figure whose base is a curve, and from which the two upwardly-rising sides converge to the opposite and smaller side, near the top.

Having thus described my design, what I claim as new, and desire to secure by Letters Patent, is—

The design shown and described.

RAPHAEL M. SELDIS.
